UNITED STATES PATENT OFFICE.

JOHN J. SCHRAG, OF TOLEDO, OHIO, ASSIGNOR OF ONE-HALF TO THOMAS L. GOURLEY, OF TOLEDO, OHIO.

SWITCH-STAND.

SPECIFICATION forming part of Letters Patent No. 707,360, dated August 19, 1902.

Application filed March 20, 1902. Serial No. 99,134. (No model.)

To all whom it may concern:

Be it known that I, JOHN J. SCHRAG, a citizen of the United States, residing at Toledo, county of Lucas, and State of Ohio, have invented certain new and useful Improvements 5 in Switch-Stands, of which the following is a specification.

My invention relates to switch-stands.

My object is the provision of a switch-stand 10 having an improved and novel locking device which will be protected against water and snow and capable of rapid and easy manipulation not only for switching from one track to another permanently, but where switching 15 operations can be carried on without causing the locking of the mechanisms if such is not desired.

My object is to provide a switch-stand of 20 the character described which will be adapted to automatically lock when the switch is in proper position, but provided with such novel and improved means that automatic locking will be prevented when desired, so that a series of switching operations can be 25 carried on one after the other as desired without necessitating the locking of the switch and the unlocking thereof after each switch has been thrown.

To accomplish the foregoing objects, I provide 30 a switch-stand having a locking-lever and provided with an automatic lock adapted to coöperate with means on the switch-stand to lock the lever after the switch has been thrown and improved means on the switch-stand adapted to prevent the automatic locking 35 of the lever when locking of the switch is not desired.

The invention comprises certain novel features and combinations of parts, set forth in 40 detail hereinafter and recited in the appended claims.

In the accompanying drawings, Figure 1 is 45 an elevation showing the lever locked and one of the latches closed; Fig. 2, a vertical section of Fig. 1; Fig. 3, a transverse section; Fig. 4, a detail of the locking mechanisms on the lever; Fig. 5, a detail of one of the latches, and Fig. 6 a detail illustrating how the lever is prevented from locking when the latch is 50 closed.

The numeral 1 designates the casing of the

switch-stand, which may be of any preferred form and provided at its upper portion with a head having the notches 2 for the reception of the switching-lever when the latter is 55 down.

The numeral 3 designates the target and lamp-rod, provided at its lower end with the switch-rod crank 4 and at its upper end with the usual target 5 and lamp 6, said rod extending vertically through the casing and journaled to turn therein on its longitudinal axis.

Extending out laterally from the casing 1 are the locking members or projections 7 and 65 8, corresponding to the positions the switch-tongue will assume, said projections having the recesses or sockets 9. Pivoted to the casing are latches 10, provided with heads 11. The latches are of such construction that they 70 can be thrown up and back against the casing when it is desired that the switching-lever lock with the locking projection, and the heads 11 are of proper size to fit in the sockets 9 and completely close the same and themselves to constitute an abutment for the locking-lever to prevent it from passing farther over the locking projection or for the locking mechanisms to engage with the socket, as illustrated in Fig. 6. 80

Connected to and extending out laterally from the rod 3 above the casing is an arm 12, and the switching-lever 13 is pivoted thereto at 14 in such position that when the lever is allowed to drop or is swung downwardly and 85 being in proper position it will enter one of the notches 2, and said lever being also cut out at 13' will pass over the projections 7 or 8.

The numeral 15 designates a locking-bolt pressed by a spring 16, which is located inside 90 a recessed portion 13" and is adapted to spring into cut-out portion 13' and into the socket 9. The bolt 15 has a notch 15' for receiving the ward of an ordinary key 18, which can be entered through a keyhole 17 in the lever, 95 whereby the bolt can be retracted. A plate 19 covers and protects the lock and has a lug 20, adapted to engage shoulder 21 on the bolt and limit the projection thereof by the spring.

The operation of the switch-stand is as follows: The lever 13 is utilized to switch the arm 12 and the rod 3 around to the desired 100

position, and the lever being then allowed to drop or pressed down it will enter in the notch 2, and if the latch 10 is thrown up will pass over the projection 7 or 8, and the bolt will 5 be automatically projected into locking engagement with the socket 9, whereupon the lever and the switch will be locked. To throw the switch, the key 18 is used to release and retract the bolt, whereupon the lever can be 10 swung outwardly and upwardly and turned and again made to engage with the other projection on the casing. It frequently happens that it is desired to work the switch back and forth frequently, and in such cases it is obvious 15 that the rapid manipulation of the switch would be hindered if the lever would lock each time the switch was thrown. To provide for this contingency, my improved latches are used. When swung down, with the head 20 thereof entering the socket, the socket is closed, and consequently the bolt of the lever cannot enter said socket and lock the lever; but the lever being forced over the projection abuts against the head of the latch and while 25 locking the switch against being swung open by the passing cars can be readily pulled from the projection and the switch thrown back.

Having thus described my invention, what I claim as new, and desire to secure by Letters 30 Patent, is—

1. In a switch-stand, the combination with a frame or casing, of a switching-lever, a de-

vice on the frame or casing adapted for engagement and locking with said lever when the latter is in a predetermined position in 35 relation thereto, and a movable abutment adapted to be positioned in advance of the lever to arrest the movement of said lever and prevent it from assuming said predetermined position.

2. In a switch-stand, the combination with a frame or casing, of a switching-lever, a projecting member on the casing, provided with a socket, a lock on the lever adapted to engage said socket, and a movable latch on the 45 casing or frame which is adapted to be fitted into the socket and to constitute an abutment to prevent the lever from assuming a position where its lock will engage the socket.

3. In a switch-stand, the combination with 50 a frame or casing, of a switching-lever, a projecting member on the casing, provided with a socket, a lock on the lever adapted to engage said socket, a pivoted latch having a head adapted to be made to fit into the socket 55 and to constitute an abutment for the lever to prevent the latter from assuming a position where its lock will engage the socket.

In testimony whereof I hereunto affix my signature in presence of two witnesses.

JOHN J. SCHRAG.
